A. L. Chrisman
INVENTOR
BY Victor J. Evans

ATTORNEY

UNITED STATES PATENT OFFICE.

ARTHUR L. CHRISMAN, OF SPRINGFIELD, ILLINOIS.

CAN OPENER.

Application filed September 1, 1923. Serial No. 660,579.

To all whom it may concern:

Be it known that I, ARTHUR L. CHRISMAN, a citizen of the United States, residing at Springfield, in the county of Sangamon and State of Illinois, have invented new and useful Improvements in Can Openers, of which the following is a specification.

This invention relates to can openers, and an object of the invention is to provide a can opener which is comparatively simple in construction, and which will cut the top from a tin can in a clean smooth manner, and will not leave ragged edges on the can which have a tendency to tear or cut the food as it is removed from the can.

Another object of this invention is to provide a can opener which will open the top of a can quickly and easily and will not require a skilled operator to operate it.

Other objects of the invention will appear in the following detailed description taken in connection with the accompanying drawing wherein:—

Fig. 1 is a side elevation of the improved can opener.

Fig. 2 is a plan view of the can opener.

Fig. 3 is a detail section taken on the line 3—3 of Fig. 2.

Fig. 4 is a side elevation of a modified form of the can opener.

Fig. 5 is a plan view of the modified form of can opener.

Referring more particularly to the drawings, the improved can opener comprises a handle 1 which has a ring 2 on one end thereof. The end of the handle 1 remote from the ring 2 is flattened, as clearly shown in Fig. 1 of the drawings and it has an inserting point 3 formed thereon. The inserting point is offset laterally from the main body of the handle 1 and is adapted to be inserted into the top of a can for forming an opening therein through which the point 4 of the cutting blade 5 may be inserted. The cutting blade 5 is curved, transversely and it is also slightly curved longitudinally, as clearly shown in Figs. 1 and 2. The convex edge 6 of the blade 5 is sharpened for cutting the metal of the can.

The blade 5 is curved transversely as shown in Fig. 2 of the drawings for properly fitting within a can to facilitate the removal of the top therefrom. The blade 5 is attached in any suitable manner preferably by rivets 7 to the handle 1. A guard 8 is

pivotedly connected by means of the rivet 9 to the blade 5 and it has a hook 10 formed upon one end which hooks over the cutting edge of the blade 5 and rides about the upper surface of the edge of a can to facilitate the guiding movement of the opener. The guard 8 has a transversely extending head 11 formed upon its end remote from the transverse guiding hook 10, and the head 11 has a biting tooth 12 formed thereon which extends entirely across the head and is adapted to bite into the rim of a top of a can to form a fulcrum for the pivotal movement of the handle of the can opener when opening the can.

To operate the improved can opener, an opening is made in the top of the can adjacent the rim by means of the point 3 after which the point 4 of the knife blade 5 is inserted through the opening, and the handle is pulled down until the pawl or head 11 rests on the edge of the can. The handle is moved downwardly which moves the cutting blade 5 upwardly, cutting the top of the can. After the cut has been made, the handle is raised to a substantially vertical position and the knife is pushed forwardly along the can after which the above operation is repeated.

In Figs. 4 and 5 of the drawings, a modified form of the can opener is shown in which the handle 1^a has the transversely curved blade 5^a attached thereto in the same manner in which the blade 5 is attached to the handle 1. The fulcrum 6^a, of the modified form of the can opener, is, however, attached rigidly to the handle 1^a preferably by means of the rivets 7^a which also serves to attach the blade 5^a to the handle. The fulcrum 6^a has its biting ridge 12^a serrated as shown at 13^a so if it is so desired the biting ridge or edge 12^a may be smooth throughout its length similar to the biting tooth or ridge 12.

If it is desired to cut the top entirely from the can, when the top has been almost cut loose from the can, it is necessary to pry the top outwardly and hold it with the fingers while the last cut is made.

It is, of course, to be understood that the invention may be constructed in other manners and the parts associated in different relations and, therefore, I do not desire to be limited in any manner except as set forth in the claims hereunto appended.

Having thus described my invention what I claim is:

1. A can opener including a handle having one end offset, an inserting point formed on the offset end in parallel relation with the handle, a cutting blade attached to the handle adjacent the offset end and disposed parallel with the inserting point, a guard arm pivotally connected to the handle and normally extended transversely of the cutting blade, a hook at one end of the guard arm and a bearing head at the other end.
2. A can opener including a handle having one end offset, an inserting point at the outer end of the offset extending in a par-

allel plane with the handle, a cutting blade rigidly secured to the offset end of the handle and arranged parallel with the inserting point in spaced relation therewith, a guard arm pivotally connected to the offset end of the handle and normally positioned transversely of the handle, a hook upon one end of the guard arm, a transverse bearing head on the other end of the guard arm and biting teeth carried by said head.

In testimony whereof I affix my signature.

ARTHUR L. CHRISMAN.
